CLAIM

The ornamental design for a machine control panel, as shown and described.

DESCRIPTION

FIG. 1 is a front view of a machine control panel showing our new design;

FIG. 2 is a rear view thereof;

FIG. 3 is a left side view thereof which is a mirror image of the right side view not shown; and,

FIG. 4 is a top view thereof which is a mirror image of the bottom view thereof, not shown.

The broken line showing of elements are for illustrative purposes only and form no part of the claimed invention.
